UNITED STATES PATENT OFFICE.

GEORGE L. PROTZ, OF CLOVIS, NEW MEXICO.

FUEL-ECONOMIZER.

1,392,447.

Specification of Letters Patent.

Patented Oct. 4, 1921.

Application filed April 20, 1918. Serial No. 229,715.

To all whom it may concern:

Be it known that I, GEORGE L. PROTZ, a citizen of the United States, residing at Clovis, in the county of Curry and State 5 of New Mexico, have invented a certain new and useful Improvement in Fuel-Economizers, of which the following is a full, clear, concise, and exact description, reference being had to the accompanying drawings, 10 forming a part of this specification.

The invention relates to fuel economizers and is herein shown and described as co-operating with a combustion chamber in which the draft is created by the existence 15 of a partial vacuum, which is created by the expansion of exhaust steam or other similar expansible medium.

It is one of the objects of the invention to augment the vacuum created by this expansion. 20

It is a further object of the invention to provide a means for accomplishing this end which is extremely simple and inexpensive in construction, and which may be easily 25 installed for operation. It is an added object of the invention to provide the device with a means whereby the same may be regulated, so that the device will operate properly under various conditions, and to 30 accomplish this from a point which may be remote from the device itself and within access of the person in control.

The invention will be herein explained in conjunction with a locomotive boiler in 35 which the exhaust steam causes a partial vacuum to exist which creates draft in the fire box of the locomotive, before it is discharged through the smoke stack of the engine. The embodiment of the invention as 40 herein illustrated contemplates the use of a device which is interposed at any suitable point between the exhaust nozzle and the smoke stack or outlet of the engine, and which will not cause any back pressure when 45 the steam is discharged or emitted from the nozzle.

The invention will be more readily understood when read in conjunction with the accompanying drawings which will be explained in detail, and in which—

Figure 1 is a central longitudinal section of the forward end of a locomotive boiler showing the device applied for use; and

Fig. 2 is a perspective view of a portion 55 of the device shown in Fig. 1.

The invention consists of the member 10

and its association with various devices which may be such as illustrated in the drawings. As illustrated in the drawings this member 10 may be inserted through the smoke stack 11 and is of a length sufficient to extend beyond each end thereof. This member may be permanently fixed to the smoke stack or may be movably held with relation thereto, as found desirable. The member 10 consists of the parallel portions 12 and 13 and the transverse portion 14, which may be removably fastened by the clips 15 and 16 to the smoke stack of the engine. To the uppermost end of the member 10 may be attached the link 17, which in turn is connected to the bell crank lever 18. To this bell crank lever is attached the operating rod 19 which extends to the engine cab where it is within access to the operator. The transverse portion 14 of the member 10 is arranged directly above the nozzle 20 and is spaced a suitable distance therefrom so as not to interfere with the free escape of the steam when same is discharged from the nozzle. This arrangement eliminates any possibility of back pressure in the nozzle which would interfere with the proper operation thereof. The nozzle 20 is arranged in the usual manner in front of the fire tubes 21, but has its upper extremity arranged within the housing generally designated 22, which is composed of the diaphragm 23 and the wire screen portion 24.

By arranging the member 10 above the nozzle so that the same is in the path of the exhaust steam when it is emitted from the nozzle the exhaust steam strikes the member 10 and is split prior to entering the stack. This causes the stack to be completely filled with exhaust steam which considerably augments the vacuum which exists in the forward portion of the engine. This causes an increased draft in the fire box and results in the consumption of more of the products of combustion in the heating medium, which naturally increases the efficiency of the engine and reduces the fuel consumption materially. By manipulating the lever mechanism so that the portion 14 of the device may assume various positions or distances from the nozzle and the stack, the device may be regulated to compensate for various contingencies which may present themselves, such as variations in the quality 110 of the heating medium, atmospheric or other conditions.

From the foregoing explanation of the device it can be seen that an extremely simple construction is provided whereby the draft in a fire box may be augmented without interfering with the free escape of the expandible medium, and that the products of combustion will be thoroughly consumed, which thus reduces the amount of fuel necessary to perform a given amount of work.

10 Having shown and described one form of the invention, it is obvious that changes and modifications may be resorted to without departing from the spirit of the invention.

15 What I claim and desire to cover by Letters Patent is:

1. In a device of the class described the combination of a chamber having an outlet, a fire box and a communication between the fire box and the chamber, an exhaust port 20 exhausting into the chamber and a bar positioned in the chamber and arranged between the exhaust port and the outlet transversely to the outlet and exhaust port, said bar per-

mitting the exhaust from the exhaust port to at all times pass into the outlet, said bar 25 being secured for movement relatively to the exhaust port and outlet and having means connected thereto for actuating the same.

2. In a device of the class described the combination of a chamber having an outlet, 30 a fire box and a communication between the fire box and the chamber, an exhaust port exhausting into the chamber, and a member having a portion positioned in the chamber and arranged between the exhaust port and the outlet, said portion permitting the exhaust from the exhaust port to at all times pass into the outlet, said member having a portion which is arranged transversely to the exhaust port, and a portion extending 40 through the outlet, said member being secured for longitudinal movement and having means provided for actuating the same.

In witness whereof, I hereunto subscribe my name this 30th day of March A. D., 1918. 45

GEORGE L. PROTZ.
